No. 802,231.

PATENTED OCT. 17, 1905.

A. J. NEFF.

CABLE GRIP.

APPLICATION FILED FEB. 27, 1905.

UNITED STATES PATENT OFFICE.

ASA J. NEFF, OF HOUSTON, TEXAS.

CABLE-GRIP.

No. 802,281.

Specification of Letters Patent.

Patented Oct. 17, 1905.

Application filed February 27, 1905. Serial No. 247,507.

To all whom it may concern:

Be it known that I, ASA J. NEFF, a citizen of the United States, and a resident of Houston, in the county of Harris and State of Texas, have invented a new and Improved Cable-Grip, of which the following is a full, clear, and exact description.

This invention relates to grips to be used in connection with cableways.

10 The object of the invention is to produce a grip of simple construction which will operate to grasp the moving cable firmly and which will operate automatically to apply its grasping force when a load upon the grip is 15 applied.

Reference is to be had to the accompanying drawings, forming a part of this specification, in which drawings like characters of reference indicate like parts in the several views, 20 and in which—

Figure 1 is a perspective showing the device in practical operation, a portion of the controlling-lever being broken away. Fig. 2 is a side elevation of the grip, showing the 25 same in open or released relation, certain parts being broken away. Fig. 3 is a substantially central vertical section taken through the grip with the parts in the relation shown in Fig. 2. Fig. 4 is a rear elevation of the body of the clamp of the grip, and Fig. 5 is a plan of the clamping-nut.

Referring more particularly to the parts, 1 represents the cable, which is preferably endless and which is supposed to be moved in order to advance the load or loads drawn by the 35 cable. Such cables are used largely in excavating works of all kinds and in various engineering operations. They are usually formed of twisted strands of wire or similar 40 material.

The grip 2 comprises a clamp 3, said clamp having a body 4, which consists of a substantially triangular plate massive in structure, as shown, and formed at its upper edge into 45 a hook or jaw 5, adapted to receive the cable 1, as indicated most clearly in Fig. 3. The side edges of the body 4 preferably converge toward its lower portion, near which part the body is formed with a bore 6, which receives 50 an eccentric-pin 7, said eccentric-pin having an enlarged eccentric head 8. Upon this eccentric head 8 a movable jaw 9 is attached, the same being provided with an opening 10, which receives nicely the head 8, as indicated 55 in Fig. 2. This eccentric-pin 7 is preferably

formed integrally with a lever 11, projecting laterally from the same, as shown.

At a suitable point upon the lever 11 a clevis or shackle 12 is attached, the said shackle affording means for attaching a drag-cable 13, 60 as shown, the said drag-cable being provided with a head 14, having an eye 15 receiving the clevis, as indicated.

The extremity of the eccentric-pin 7 is threaded, as shown, and projects into the recess 16, 65 formed at the back of the body 4, in which recess a spanner-nut 17 is seated, as shown. The lower extremity of the lever 11 is preferably formed into a handle 18 for the purpose of moving the lever manually when desired. 70

The operation of the grip will be most clearly understood from an inspection of Fig. 3, and in this view the parts are shown in the relation such as to maintain the grip in a released condition. At this time the central axis of the head is disposed below the central axis of the pin 7, and this position of the parts would correspond to the relation in which they are shown in Fig. 2. If the lever 11 is 80 moved into the position indicated in Fig. 1, the axis of the head 8 will move into the position above the axis of the pin 7 and will operate to project the jaw 9 upward, in this way pressing its gripping-face against the under 85 side of the cable, as will be readily understood. The drag-cable 13, to which the load will be attached, operates to apply the lever in the manner suggested, and hence the load itself operates automatically to maintain the 90 grasp of the grip upon the cable. When it is desired to release the grip, manual force would be applied to the lever in the manner suggested above. 95

The grip may be applied or released at will anywhere along the cable and while the cable is in motion, provided the cable does not move over three hundred or four hundred feet per minute.

The grip described is evidently very simple 100 in construction and easily applied so as to do its work effectively.

Having thus described my invention, I claim as new and desire to secure by Letters Patent—

1. In a device of the class described, in combination, a clamp comprising a body and a movable jaw, a pin rotatably mounted in said body and having an eccentric head received in said movable jaw, a hand-lever carrying 110

105

said pin, and a drag-cable attached to said lever near said pin.

2. In a device of the class described, in combination, a clamp comprising a body and a movable jaw, said movable jaw having an opening, a hand-lever having a laterally-projecting pin at the extremity thereof rotatably mounted in said body, said pin having an eccentric head fitting in said opening, and means

for attaching a drag-line to said hand-lever to near said pin.

In testimony whereof I have signed my name to this specification in the presence of two subscribing witnesses.

ASA. J. NEFF.
